H. Spillman,

Truss.

No. 91,522.

Patented Sept. 7, 1869.

United States Patent Office.

HENRY SPILLMANN, OF NEW ORLEANS, LOUISIANA.

Letters Patent No. 94,522, dated September 7, 1869.

IMPROVED TRUSS.

The Schedule referred to in these Letters Patent and making part of the same.

To all whom it may concern:

Be it known that I, HENRY SPILLMANN, of the city of New Orleans, State of Louisiana, have invented a certain new, useful, and improved Truss; and I do hereby declare the following to be a full, clear, and exact description of the same, reference being had to the annexed drawing, making a part of this specification, on which it is shown in connection with the ends of the band which holds it in position on the body of the subject.

My invention consists of a peculiarly-formed metallic frame, to which the pads are secured, and which is provided with articulating notched levers at its two extremities, in combination with an elastic body-band, that is provided with metallic tips, in which pins are fixed for adjusting and holding the said notched levers in any given position, and elongated apertures are made to establish the connection of the said band with the said frame.

But my invention will be better understood by referring to the drawing, on which all that I claim as of my invention is clearly shown.

On the drawing—

A. is the metallic frame, to which I have referred, to which the pads B are secured, as shown. This frame should be made as light as is compatible with a due regard to strength, and covered with linen, or other proper material, in order to prevent chafing or irritation of the parts of the body of the wearer, with which it may come in contact. It is curved according to the size of the person for whom it is intended.

The pads B are made of red cedar, or other non-absorbing wood, or of glass, china, or ivory.

At the extremities of the frame A are pivoted the two notched levers, C C', in such manner that they will articulate freely at the points of connection a a'.

These levers are provided with three notches, each as shown, so that they can be adjusted on the pins b b', and regulate the pressure on the pads B according to the nature of the hernia or orifices against which they impinge.

The pins b b' project from plates D D', which are respectively fixed on the ends of the body-band, and in which the elongated slots c c' are made of the form as shown, to receive the pins d d', that project from the frame A.

The body-band is composed of leather at its extremities, in order the better to secure the plates D D' thereto, but elsewhere, that is to say, in its central portion, of India-rubber cloth, or some other equally elastic fabric.

In the use of my truss, if a very considerable pressure is necessary, the levers C C' are adjusted on the pins b b' by slipping the outer notches in the former over the latter. If a less pressure is required, the adjustment is as shown on the drawing, that is to say, the pins b b' are placed in the central notches; and if only a moderate or gentle pressure is needed, then the inside notches are brought into connection with said pins, for it will be observed that the relation and

action of the levers C C' on the frame A, is such that the latter is thrown out at its upper edge, and brought toward the body of the wearer at its lower edge, to which the pads B are secured, to a greater or less extent, accordingly as the said levers are adjusted on the pins b b' through the agency of the outer or inner notches in the former. The total disconnection of the levers C C' from the pins b b', takes off nearly all the pressure of the pads, or, in other words, reduces it to such extent as to make it almost inappreciable to the wearer, whilst yet fully sufficient for some phases of hernia, and some stages of its progress toward a cure.

An examination of my improvement will show that it possesses the following advantages over all other trusses now in use:

There are no springs in it, no back pads, no straps around the legs, no metallic or other hard part crossing the spine, but in its back sections, consisting of an elastic belt or band, which, yielding easily to every movement of the body of the wearer, is scarcely felt by him.

It completely prevents any pressure except through the pads, where the pressure is regulated and controlled, at the pleasure of the wearer, by a simple adjustment of the levers C C'.

It is so constructed that the metallic portion of it does not lie over any bone that is near the skin, and hence no irritation can possibly occur, but only over the lower portion of the abdomen, to which it is fitted before it is put on.

It does not require to be made of costly tempered steel, but is as effective when constructed of one metal as another, provided always the same possesses sufficient strength to sustain the slight strain to which it is necessarily sometimes subjected.

It maintains itself in proper position better than any other truss of which I have any knowledge.

It can be used for a single rupture on the right or the left, or with two pads, as shown, for a double rupture.

When used for a single rupture, the frame A protects the unruptured side by a gentle pressure, which is of great importance.

Finally, when properly fitted to the wearer, it gives less trouble in every way than any other in existence, is more easily worn, and will last longer.

Having thus described my invention,

What I claim, and desire to secure by Letters Patent, is—

The metallic frame A, when provided with the notched levers C C', and otherwise fitted and constructed as herein described, in combination with an elastic body-band or belt, to which the plates D D' are secured, when these plates are provided with the pins b b' and the elongated apertures c c', substantially as herein described, for the purpose set forth.

H. SPILLMANN.
